G. CANELSTEIN

Des. 105,198

TEXTILE FABRIC

Filed June 10,

INVENTOR
G. G. Canelstein

UNITED STATES PATENT OFFICE

105,198

DESIGN FOR A TEXTILE FABRIC

Gotel Canelstein, New York, N. Y.

Application June 10, 1937, Serial No. 69,772

Term of patent 3½ years

To all whom it may concern:

Be it known that I, Gotel Canelstein, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

I claim:

The ornamental design for a textile fabric, substantially as shown.

GOTEL CANELSTEIN.
